UNITED STATES PATENT OFFICE.

GEORGE CRAWFORD EASTMAN, OF LEWISTON, MAINE, ASSIGNOR TO
ISAAC C. MERRILL, OF SAME PLACE.

TUG.

SPECIFICATION forming part of Letters Patent No. 293,642, dated February 19, 1884.

Application filed October 9, 1883. (No model.)

To all whom it may concern:

Be it known that I, GEORGE CRAWFORD EASTMAN, of Lewiston, in the county of Androscoggin, of the State of Maine, have invented a new and useful Improvement in Carriage Shaft or Thill Supporters; and I do hereby declare the same to be described in the following specification and represented in the accompanying drawings, of which—

10 Figure 1 is a front view, Fig. 2 a side elevation, Fig. 3 a longitudinal section, and Fig. 4 a transverse section, of a shaft-supporter of my improved kind. Figs. 5 and 6 are opposite side views of one of the metallic body parts B B', to be hereinafter described.

The invention relates to the kind of carriage-shaft supporters described and represented in the United States Patent numbered 199,148, granted to me January 15, 20 1878. In my present shaft-supporter, the leather annular packing A has its opposite edges in grooves *a a* in the two next adjacent metallic body parts B B', which, formed as represented, are connected by four screws, C, 25 D, E, and F, going through one of such parts and screwed into the other, so as to draw them closely against the packing between them and with the grooves to hold it firmly in place. Each of the said parts B and B' is composed not 30 only of a ring channeled or grooved on its inner side, as shown at *a* in Fig. 4, but of two arms or projections, one of which extends upward and the other downward from it, as represented, they being in one piece with the ring. 35 Each of such arms or projections is perforated to receive two of the said screws. The packing A is of stiff and thick leather, and when inserted in the said grooves has its outer and inner curved surfaces about even or flush with 40 those of the two rings, the packing by this arrangement being exposed in a manner to admit of the loop I, hereinafter referred to, being lapped on and connected to it by rivets going through them, such loop being first projected 45 through eyes H H. The screw D, I provide with a buckle-tongue, G, pivoted on the said screw, and extended up and lapping on the uppermost screw, C. Furthermore, I provide each of the body parts B B' with one of 50 two elongated eyes, H H, to extend from it,

as shown in Figs. 5 and 6, such eyes being to support and receive a loop, I, of leather, extended through them, as represented, and fastened to the ring of packing by rivets, tacks, or other suitable means. This loop is to receive a strap depending from the saddle of the harness and buckled into the upper part of the supporter. A metallic tube or friction-roller, d, encompasses that part of the shank of each of the screws C and F which is between 55 the two parts B B', such roller being free to revolve on such shank. The lower roller is to support the saddle-girth arranged to extend between the lower portions of said parts BB'. By having the buckle-tongue instead of a bridge 60 and stud and a metallic loop fastened to the two metallic parts of the supporter, as in that shown in my said patent, I am enabled to draw such parts, by their screws, closer upon the packing, and thereby better hold it in place, it 65 being in practice, as I have found, apt to work loose or get out of place when the supporter is made as represented in such patent.

I do not claim a thill-tug constructed as shown in the United States Patent No. 47,903, 70 in which the leather packing is covered on its outer surface by its holding-rings, and such rings have no eyes extending from them to receive a leather loop going through them and fastened to the packing, as is the case in my thill-supporter. Furthermore, the said patented thill-tug has a buckle pivoted at its middle to the rings of the said tug, whereas in my supporter I have no such buckle, but simply have rigid projections from the rings and four screws 75 to go through such projections; and on one of such screws I have a buckle-tongue, to extend therefrom to another of such screws. In the United States Patent No. 199,148, hereinbefore mentioned, the rings for supporting the 80 packing are, like those in the Patent No. 47,903, connected by two screws only, whereas four screws are necessary to the connection of the parts B B' of my thill-supporter.

I claim—

1. The shaft-supporter having its metallic parts B B' provided with grooves to receive the edge of the packing and connected by screws arranged in them, the said parts, in combination with the packing A, arranged between 95 90 95 100

the rings of such parts, with its inner and outer peripheries essentially even or flush with the next contiguous surfaces of such rings, all substantially as set forth.

5 2. The shaft-supporter composed of the two grooved metallic parts B B', the leather packing A, and their connection-screws C, D, E, and F, a buckling-tongue, G, adapted to two of the screws, and a buckling-loop, I, of leather

or other suitable material, arranged in eyes to be extended from the said two parts and connected to the packing between them, as specified.

GEORGE CRAWFORD EASTMAN.
